his ATTORNEY

UNITED STATES PATENT OFFICE

OSCAR S. FIELD, OF ROCHESTER, NEW YORK, ASSIGNOR TO GENERAL RAILWAY SIGNAL COMPANY, OF ROCHESTER, NEW YORK

CIRCUIT CONTROLLER

Application filed March 20, 1930. Serial No. 437,445.

This invention relates in general to circuit controllers, and has more particular reference to a circuit controller adapted for use with, and operated by, a railway track switch.

The controller of this invention is somewhat similar to that disclosed in the patent to W. S. Henry, 1,332,215 granted March 2, 1920.

10 In controllers of the character in question, one or more movable contacts are arranged to be moved between corresponding front and back fixed contacts for making and breaking circuits for various purposes, the movable contacts being in an intermediate or neutral position during the throw of its track switch, and making front or back contact, according as the track switch is normal or reverse, or vice-versa.

20 One of the objects of the present invention is to provide cam operating means for the movable contacts whereby to accurately and positively move the contacts, with means for adjusting the cam operating means for adapting the circuit controller to be used with track switches having various lengths of throw such as is met with in practice.

25 A further object of the present invention is to provide means for automatically moving the movable contacts to an intermediate or neutral position should the connection between the track switch and circuit controller become broken, to thereby indicate the faulty condition of the apparatus.

35 Further objects, purposes and characteristic features of the present invention will appear as the description progresses, reference being made to the accompanying drawing, showing, solely by way of example, and in no manner in a limiting sense, one form which the invention can assume. In the drawing:

Fig. 1 is a plan view of a device embodying the present invention.

45 Fig. 2 is a sectional view on the line 2—2 of Fig. 1, viewed in the direction of the arrows.

Fig. 3 is a sectional view on line 3—3 of Fig. 1, viewed in the direction of the arrows.

50 Fig. 4 is a schematic view showing differ-

ent operative positions of portions of the device.

Referring to the drawing, there is shown a casing 1, having a cover 2, hinged at 3, and furnished with a closing hasp 4. Passing through the casing is a spindle 5, carrying a crank arm 6, with a connecting pin 7 for connecting the crank to a moving part of a track switch (not shown) whereby to rock the shaft 5 when the track switch is moved.

Within the casing 1 is an insulating block 8, carrying sets of movable and fixed contacts, there being shown, in the present case, four sets of such contacts merely by way of example. Each set of contacts comprises a back fixed contact 9, a front fixed contact 10, and a movable contact 11. Each movable contact 11 is carried on an arm 12, pivoted at 13 to a fixed arm 14 connected to the insulating member 8. The pivoted arms 12 are all connected to a bar 15 to which is attached an operating arm 16 having a fork 17 supported by the shaft 5 whereby to be slidable thereon.

Carried by shaft 5 are operating cam members 18 and 19 which can be separately adjusted on shaft 5 by means of threaded bolts 20 cooperating with correspondingly threaded portions 20¹ on shaft 5, and after adjustment, can be clamped in position on the shaft by bolts 21.

Carried by the operating arm 16 is a transverse pin carrying opposite rollers 22 and 23 for cooperating, respectively, with cams 18 and 19.

On rocking movement of shaft 5, due to movement of the driving track switch, the cams 18 and 19, clamped to shaft 5, move over the rollers 22 and 23 to move operating arm 16 to shift contact 11 from its shown position (Fig. 2), that is, the normal position, first to neutral, where contact 11 is intermediate its fixed contacts, and then to its reverse position, where contact 11 is in contact with the back contact 9.

The operation of cams 18 and 19, on the rollers 22 and 23 is diagrammatically illustrated in Fig. 4, the rollers being here shown as moving, over the cam, for the sake of

clearness in illustration and explanation, although, in actual operation, as can be readily seen from Fig. 1, the cams 18 and 19 are carried by the shaft 5 and move over the rollers.

5 In Fig. 4 the rollers 22 and 23 are shown in four different operative positions, 24, 25, 26 and 27. With the parts positioned as shown in the drawing, movable contact 11 is against fixed contact 10, which is the position corresponding to the track switch set normal. On first movement of the track switch, shaft 5 is turned in a counter-clockwise direction to thereby move the cams 18 and 19. Roller 22 is first operated on by 10 cam 18, the portion 18¹ thereof moving roller 22 outwardly away from the spindle 5 so that the roller assumes the position shown at 25. Further movement of the shaft and cams merely hold the rollers in set position, 15 with the movable contact 11 positioned midway between the fixed contacts 9 and 10, that is, held in neutral position. This continues during the throw of the track switch and at the completion of the switch throw, the projecting portion 19¹ of cam 19 moves roller 23 outwardly from the shaft 5 to change it from the position shown at 26 to that shown at 27 which results in moving the movable contact 11 into contact with fixed contact 9.

30 On reverse movement of the track switch a reverse sequence of operation takes place.

It is thus clear that on the first movement of the track switch, the contacts are opened, and are held opened until the switch completes its throw at which time the contacts are closed in the opposite direction. With track switches having various lengths of throw, the shaft 5 will be rocked through varying degrees of arc so that the contacts 35 would be made and broken during the throwing of the track switch, unless means are provided for adjusting for different lengths of throwing. The means provided in this case is the adjustment whereby the individual cams 18 and 19 can be rotated on the shaft 5 to thereby vary the distance between the cam portions 18¹ and 19¹. In this manner adjustment can be made so that operation by the track switch will always result 40 in opening a contact at the initiation of the throw of the switch, and closing the contact in the reverse direction at the completion of the throw of the track switch.

As shown in Fig. 3, the shaft 5 extends 55 into a casing 28 and has a squared portion 5¹ to which is fixed a crank arm 29 connected by means of a link 30 to a spring biased arm 31 biased by spring 32 in a clockwise direction. The crank 29 assumes the position 60 shown when the track switch is set for main line traffic, and contacts 10 and 11 are in contact. In this position arm 31 has been moved counter-clockwise so as to compress spring 32.

65 Should the physical connection between the

track switch and the operating crank 6 become broken, or should the drive connection be broken at any point, spring 32 operates to move shaft 5 so as to open contact 11 and leave it in neutral position. The crank arm 29 assumes a symmetrical position to the other side of the connection point between link 30 and arm 31, when the track switch is set reverse, to likewise compress spring 32, so that break of the drive connection in such circumstance results in moving the movable contact 11 into neutral position. The crank arm 29 is in a dead center position when the movable contact 11 is in its neutral position, whereby to prevent spring 32 from moving contact 11 beyond its neutral position. The crank arm 29 and casing 28 and associated parts are arranged, as shown in Fig. 1, so that they can be reversed in position to place the crank on the other side of casing 2, and the spring returned casing 28 at the present crank side of casing 2. Likewise an inlet conduit 33 is carried by a plate 33¹ which can be attached to either side of the casing so as to position the parts either right or left handed. The above rather specific description of one form of the present invention is given solely by way of illustration, and is not intended, in any manner whatsoever, in a limiting sense. Obviously, the invention can assume many different physical forms, and is susceptible of numerous modifications, and all such forms and modifications are intended to be covered by this application, as come within the scope of the appended claims. Having described my invention, I now claim:

1. In a circuit controller for railway track switches and the like, a movable contact, a front and a back contact, a shaft for operating the movable contact from one to the other of the fixed contacts, drive means for said shaft, a resiliently biased arm, a toggle connecting the arm to the shaft for moving the movable contact to a neutral position upon the drive means becoming disconnected from said shaft, the toggle being on dead center when the contact is in neutral position thus to prevent the biased arm from moving the contact beyond neutral position.
2. In a circuit controller for railway track switches and the like, a movable contact, a front and a back contact, a shaft for operating the movable contact from one to the other of the fixed contacts, drive means for said shaft, a pivoted arm, a toggle member connecting the arm to the shaft, and resilient means acting on the pivoted arm to straighten the toggle and position the contact in neutral position, whereby to automatically move the contact to neutral upon disconnection of the drive from said shaft.
3. In a

therebetween, a shaft, and two cams on the shaft for moving the movable contact from one extreme position, through neutral to another extreme position, an operating portion 5 on one cam for moving the contact from one extreme position to neutral, a second operating portion on the other cam means for moving the contact from neutral to the other extreme position, each cam including a single 10 casting, a hole in the casting to receive the shaft, a threaded pin passing through the casting and held against endwise movement therein, a split portion running into the hole, and a clamping bolt passing through the 15 split portion.

4. In a circuit controller, in combination, a contact, a shaft, teeth formed on the shaft, a cam on the shaft and positioned over the teeth, for moving the contact, the cam includ- 20 ing a single casting, a circular opening there- in to receive the shaft, a threaded spindle in the casting and held against endwise move- ment therein and engaging with said teeth, a split portion extending from one edge of the 25 casting into said opening, and a clamping bolt in the casting passing across the split por- tions.

In testimony whereof I affix my signature.
OSCAR S. FIELD.
